US0D1071834S

(12) **United States Design Patent** (10) Patent No.: **US D1,071,834 S**
(45) Date of Patent: ** Apr. 22, 2025

(54) **TIRE**

(71) Applicant: **COMPAGNIE GENERALE DES ETABLISSEMENTS MICHELIN, Clermont-Ferrand (FR)**

(72) Inventor: **Arnaud Larregain, Clermont-Ferrand (FR)**

(73) Assignee: **Compagnie Generale Des Etablissements Michelin, Clermont-Ferrand (FR)**

(**) Term: **15 Years**

(21) Appl. No.: **29/887,983**

(22) Filed: **Mar. 27, 2023**

(30) **Foreign Application Priority Data**

Sep. 28, 2022 (EM) 009189491
(51) **LOC (15) Cl.** **12-15**
(52) **U.S. Cl.** ..... **USPC D12/605**
(58) **Field of Classification Search**
USPC D12/604, 605
CPC B60C 13/00; B60C 1/00
See application file for complete search history.

(74) Attorney, Agent, or Firm — Dickinson Wright PLLC

(57) **CLAIM**

The ornamental design for a tire, as shown and described.

DESCRIPTION

FIG. 1 is a perspective view of the tire of my design; FIG. 2 is a front elevation view of the tire of my design; FIG. 3 is a side elevation view of the tire of my design; and, FIG. 4 is a side elevation view of the tire of my design, taken from the opposite side of that shown in FIG. 3. The dash-dot-dot-dash lines define the boundaries of the claim. The broken line disclosure in the drawings depicts environmental subject matter forming no part of the claimed design.

1 Claim, 4 Drawing Sheets
